[57] CLAIM

The ornamental design for a hood/fender unit for a truck, as shown and described.

DESCRIPTION

FIG. 1 is a front perspective view of the hood/fender unit for a truck showing my new design;

FIG. 2 is a top plan view of the inventive design;

FIG. 3 is a front elevation view of the inventive design;

FIG. 4 is a side elevation view of the left side of FIG. 1, the

opposite side elevation view being identical;

FIG. 5 is a rear elevation view of the inventive design; and,

FIG. 6 is a bottom plan view of the inventive design.
